Des. 240,710
Patented July 27, 1976

240,710

PLAYGROUND FITTING

Dwight C. Shaneour, Hillsdale, Mich., assignor to
Quality Industries, Inc., Hillsdale, Mich.

Filed Oct. 2, 1975, Ser. No. 618,904

Term of patent 14 years

Int. Cl. D8—08

U.S. Cl. D8—235

FIG. 1

FIG. 2

FIG. 3

FIG. 4

FIG. 5

FIG. 6

FIG. 1 is a side elevational view of a playground fitting in accord with my new design,

FIG. 2 is an elevational view of the opposite side of the fitting illustrated in FIG. 1,

FIG. 3 is an elevational view as taken from the left of FIG. 1,

FIG. 4 is an end elevational view as taken from the right of FIG. 1,

FIG. 5 is a top plan view of my new design as taken from the top of FIG. 1, and

FIG. 6 is a bottom view of my new design.

I claim:

The ornamental design for a playground fitting, substantially as shown.
